UNITED STATES PATENT OFFICE

JAMES F. McELROY, OF LANSING, ASSIGNOR TO THE McELROY CAR HEATING COMPANY, OF DETROIT, MICHIGAN.

SYSTEM FOR HEATING CARS.

SPECIFICATION forming part of Letters Patent No. 400,350, dated March 26, 1889.

Application filed December 2, 1887. Serial No. 256,764. (No model.)

To all whom it may concern:

Be it known that I, JAMES F. McELROY, a citizen of the United States, residing at Lansing, in the county of Ingham and State of Michigan, have invented certain new and useful Improvements in a System for Heating Cars, of which the following is a specification, reference being had to the accompanying drawing.

10 This invention relates to new and useful improvements in a system for heating cars; and the invention consists in the peculiar combination of the hot-water-circulating apparatus provided with the ordinary stove or heater 15 with means for heating the water of circulation independently from said stove or heater by means of steam supplied from the locomotive or other source of supply; and to this end my invention consists in the peculiar 20 combination and arrangement of the parts, all as more fully hereinafter set forth.

In the drawing which accompanies this specification, A represents a stove or heater of a circulating hot-water apparatus.

25 B are the radiating-pipes in the car.
C is the expansion-drum.

D is the return-connection to the stove.

E is the outgoing-connection from the stove.

30 F is the outgoing-connection from the expansion-drum to the radiating-pipes.

G is a vertical pipe or riser which connects the return end of the radiating-pipes with the expansion-drum, and to this riser are connected the outgoing and return connections 35 E D of the heater or stove.

H is a main steam-pipe, preferably arranged below the car-floor and connected with the locomotive or other available source of supply for conveying steam for heating the 40 cars of the train.

I is a steam-supply pipe controlled by a suitable valve, J, leading from the main steam-pipe into the riser G, which it enters near the upper end, and then extending down inside 45 said riser preferably continues within the lowest branch, K, of the radiating-pipes the whole length thereof, when it passes out and terminates, preferably, with a suitable air-valve or temperature-trap, L, which dis- 50 charges below the car-floor. The pipes G and K, I propose to make about two inches in di-

ameter and the steam-supply-pipe about one inch in diameter, so that when placed inside a sufficient space is left for the water of circulation equal or greater than the capacity of 55 the one and one-half inch steam-pipe, which is the ordinary size of the radiating-pipes in the car. A slight fall should be given to the pipe K, in order to carry the water of condensation in the steam-pipe to the exit L. 60 The expansion of that portion of the steam-pipe which is inclosed within the water-pipe is readily compensated for at the elbow. It is evident that this arrangement for heating the water may be used in the pipes on both 65 sides of the car; or the circulation may be so connected with the steam-pipe on one side that it will heat the water in both sides. Branches of the steam-pipe may also be carried in different directions and may jointly 70 discharge into the same or into different traps.

The operation of my system will be easily understood, as it is obvious that if steam is admitted into the steam-supply pipe I such portion of the pipe I which is in operative 75 contact with the water of circulation will impart its heat to the water and thereby form a source of heating, which may be used independent of the stove whenever the supply of steam is available; or, if desired, both heat- 80 ers may be in operation at the same time. By placing the radiating steam-pipe within the radiating hot-water pipes the heating capacity of the latter, which is generally the least effective when run in the ordinary way, is greatly 85 increased, while at the same time in my arrangement the hot-water circulation within the stove becomes short-circuited and little or no heat is wasted in the absence of fire on account of the cooling-drafts which generally 90 are created through the stoves.

I do not broadly claim the combination with a hot-water-circulating system with a steam heater or radiator in operative contact with such system and forming an independent means of heating therefor, as that forms the subject of a prior application, but claim the specific construction by means of which I have accomplished the object of maintaining a hot-water-circulating apparatus of the ordinary type as now used in railroad-cars in 95 operative condition by means of the heat de- 100

rived from steam, or, if contingencies should arise, from fire in the stove; and for this construction I claim, aside from its great simplicity, that it has the advantage of a practically-independent system of heating, as it will readily be seen that the stove can be detached (in case of necessary repair, for instance) without depriving the car of means for heating it.

10 Some of the features herein shown but not claimed are shown in my application, No. 230,339, filed March 10, 1887.

What I claim as my invention is—

15 In a car-heating system, the combination, with the lower branch, K, of the radiating-pipes of a circulating hot-water system and

the heater, of the riser G, connecting said branch with the expansion-drum, the steam-pipe I, entering the riser G near the top thereof and running downwardly through the 20 riser and through the pipe K, and the outgoing and ingoing connections D E between the riser G and the heater, substantially as described.

In testimony whereof I affix my signature, 25 in presence of two witnesses, this 22d day of November, 1887.

JAMES F. McELROY.
